MACHINE FOR MAKING AND APPLYING SPANGLES

Cesar Bustamante, New York, N. Y., assignor of one-third to Sol Bookstein, Belle Harbor, N. Y., and one-third to Boris Weisman, New York, N. Y.

Application August 22, 1942, Serial No. 455,813

15 Claims.

(Cl. 112—99)

This invention relates to spangle machines and has for its object the provision of an improved spangle machine.

Machines have heretofore been proposed for sewing pre-formed spangles to fabric. Such machines, however, are objectionable because of the fact that the spangles are tiny discs, very thin and very light, and consequently quite difficult to manipulate or to arrange in any regular order so that they can be handled by a feeding mechanism. Mechanism for handling such articles is apt to be complicated, expensive to make and unreliable in operation.

It has also been heretofore proposed to partially pre-form the spangles, leaving them connected together in a continuous strip which was fed to the stitching mechanism. Associated with this mechanism was a reciprocating knife which severed the individual spangles from the strip after the needle had entered the hole in the center of the spangle in the operation of sewing the spangle onto the fabric. This machine necessitated that cutting mechanism be positioned in close proximity to the needle of the sewing mechanism, and this was apt to lead to considerable difficulty. Moreover, the character of designs possible with such a machine was limited because of the fact that it would be impossible to sew the spangles onto the fabric in overlapped relation to one another.

The object of the present invention is to provide a spangle machine which is capable of both manufacturing the spangles from suitable material and applying them to the fabric or other sheet material to which it may be desired to attach them.

More particularly, the object of the present invention is to provide a machine in which the individual spangles are completely formed from suitable material and then transferred individually from the forming mechanism to the sewing mechanism without losing control of the individual spangles.

A feature of the invention also is the provision of a spangle machine having forming or punching mechanism which is disposed sufficiently remote from the sewing mechanism so that the design of the punching mechanism will not be restricted or impaired by its proximity to the sewing mechanism.

A further object of the invention is to provide a spangle machine which is of rugged construction and can be used for long periods of time with a minimum of servicing.

The invention will be understood from a con-

sideration of the accompanying drawings which illustrate, by way of example, a spangle machine arranged to punch the spangles out of a narrow work strip and sew them to sheet material which consists of dress fabric.

In these drawings:

Fig. 1 is a combined plan and sectional view showing the punching and transferring mechanism in plan, the section being taken horizontally through the shank of the presser foot of the sewing mechanism;

Fig. 2 is a view in elevation of the parts of the machine illustrated in Fig. 1 looking from the side of the sewing mechanism;

Fig. 3 is also a view in elevation but looking from the front;

Fig. 4 is a detailed sectional view of the punching mechanism taken on line 4—4 of Fig. 1, but with the parts in a different position; and

Figs. 5, 6 and 7 are views of fragments of sheet material having spangles applied to them in different spacing.

Referring now to these drawings, the machine has an L-shaped frame 1 which is suitably mounted on the frame of a sewing machine. The sewing machine is provided with suitable stitch-forming mechanism including a vertically reciprocating needle 2 and a presser foot 3, the needle being operatively connected in any suitable manner with the horizontal main shaft 4 of the sewing machine, these being the only parts of the sewing machine illustrated. The sewing machine mechanism may be of any appropriate construction, it being understood that the needle 2, presser foot 3 and other parts of the stitch-forming mechanism make one reciprocation and form one complete stitch for each revolution of the sewing machine main shaft 4.

One leg of L-shaped frame 1 rotatably supports an operating shaft 5, this shaft being driven from sewing machine main shaft 4 through a chain 4a and cooperating sprockets having the same number of teeth, thereby causing shaft 5 to rotate in timed relation to shaft 4. On the end of shaft 5 there is a small crank having a crank pin 6 which engages a slotted opening 7 at the rear end of a rock arm 8 so as to impart a continuous rocking movement to this arm. Arm 8 is pinned as shown at 9 to a short shaft 10 which has a bearing in the short arm of the L-shaped frame member 1. On the opposite end of shaft 10 and pinned thereto at 11 so as to rock with arm 8 there is a feed actuating member 12 (Fig. 2), which will be referred to later on.

The front end of rock arm 8 actuates a ver-

tically reciprocating punch carrier member 13. This member viewed from the front is bifurcated at its upper portion and connected by means of a pin 15 to actuating member 8 which is slotted as shown at 14 in Fig. 2. Pin 15 is squared at its central portion so as to fit the slot 14 and round at each end so as to fit round holes in the bifurcated portion of the punch carrier.

Mounted in the lower surface of punch carrier 13 there are two punches—a small punch 16 and a large punch 17. These punches are both round, and slide in openings in a guide bar 18 which projects horizontally (Fig. 4) from the lower edge of a downward extension 19 formed on the short arm of L-shaped frame member 1. 15 A die 20 is mounted on the lower surface of guide 18 but between them there is arranged a rectangular passageway for a work strip 21 from which the spangles are to be formed and punched.

In order to guide the rear end of punch carrier 13, a guide rod 22 is fixed in guide bar 18 and extends upwardly. An opening in the lower surface of carrier 13 fits the upper end of guide rod 22 with a sliding fit.

Mounted on punch carrier 13 ahead of the two punches 16 and 17 is a shaping punch 23 which coacts with a dish-like formation 24 (Fig. 2) in the upper surface of die 20. Shaping tool 23 may be heated if desired by means of an electric heater 25 to which are attached conductors 26.

The spangles may be formed out of plastic, metal or other suitable material. Also this material may have any appropriate thickness, usually a few thousands of an inch. The spangles also may have any appropriate diameter, but the customary diameter is from $\frac{1}{8}$ to $\frac{1}{4}$ of an inch.

The work strip 21, of suitable thickness and width and of indeterminate length, passes from left to right (Fig. 2) through the passageway 21 above referred to between the upper surface of die 20 and the lower surface of guide bar 18. It then passes beneath the shaping punch 23 and the two punches 16 and 17 and from thence the waste strip passes around a guide pin or roller 27 around the surface of a feed roller 28 and between this roller and a pressure roller 29, after which it is wound in any desired manner onto a take-up roll, not shown. It will be understood that punch 16 forms the hole or perforation which is to be at the center of each spangle and the punch 17 blanks out the spangles with the perforations at their centers.

Pressure roller 29 rotates freely on a shaft 30 which projects to the left (Fig. 3) from a supporting arm 31 which is pivoted at 32 to frame member 1. A helical spring 33, the tension of which can be adjusted as shown in Fig. 2, is provided to regulate the amount of pressure between rollers 29 and 28.

Main feed roll 28 is pinned to an actuating shaft 34 which is mounted for rotation on frame member 1 and which is given a step-by-step advance movement each time the punch carrier 13 reciprocates. For this purpose a pinion 35 is loosely mounted on shaft 34 (Figs. 1 and 3) which is provided on one side with an extension having in its face ratchet teeth 36. The teeth of pinion 35 are engaged by the teeth 37 of a gear sector on the outer end of one of the two arms of feed actuating member 12. This member, as previously described, rocks simultaneously with the rocking movement of rock arm 8.

The ratchet teeth 36 are engaged by similar teeth in a ratchet member 38 which is held in

yieldable engagement with the teeth 36 by means of a helical spring 39 surrounding the outer end of shaft 34. Ratchet member 38 is provided with a pin 40 which passes through a slot 41 in shaft 34 so that longitudinal movement of member 38 is provided for.

From this it will be understood that on each upward movement of punch carrier 13 pinion 35 is rotated in the clockwise direction as viewed in Fig. 2, as shown by the arrow, which causes the work strip 21 to be advanced. During the downward stroke of carrier 13 pinion 35 is rotated in the opposite direction and the coacting ratchet teeth slide over one another, ratchet member 38 yielding outwardly to permit this action. Backward rotation of ratchet member 38 is prevented by the adjustment of helical spring 33 to provide sufficient friction by means of pressure roll 29 to prevent such movement. Since at the bottom of the stroke of punch carrier 13 the punches 16 and 17 engage the work strip 21 and prevent its forward movement, a suitable amount of lost motion or back-lash between the ratchet teeth 36 and those on member 38 is provided, as indicated at 42. Hence the feeding movement of feed rolls 28 and 29 does not commence until after punch 17 has been raised sufficiently to release the work strip 21 (see Fig. 4).

It will be understood that the spangles are attached to a fabric sheet by means of the stitch-forming or sewing mechanism including needle 2 and presser foot 3. In order to attach the spangles to fabric 43 without losing control of them, a transferring device or carrier mechanism is provided which receives the individual spangles as they are punched from the work strip 21 by the punching mechanism, holds them in the position in which they are delivered by the punching mechanism and transfers them 40 while continuing to maintain them in such position, to the sewing mechanism and preferably directly onto the fabric 43 beneath the presser foot 3 and in alignment with needle 2. This transferring device or carrier mechanism is indicated generally by numeral 44 and comprises a swinging arm 45 and a stationary guard member 46 preferably arcuate in form.

Swinging arm 45 is provided at its outer end with a spangle receptacle or cup-like formation 47 adapted to receive an individual spangle such as indicated by numeral 48. At the instant the large or blanking out punch 17 pierces the work strip, swinging arm 45 is in the dotted position shown in Fig. 1, receptacle 47 being directly beneath the opening in die 20 with which punch 17 cooperates, as indicated by dotted lines in Fig. 2. As soon as the spangle is released from strip 21 by punch 17 it falls into cup 47 in this position, and arm 45 then swings to the full line position shown in Figs. 1, 2 and 3. As the spangle receptacle 47 moves out from beneath die member 20 its upper surface passes into contact with the lower downwardly sloping surface 49 of arcuate guard member 46 which holds the spangle 55 in receptacle 47 during the movement of arm 45 and prevents the spangle from being dislodged.

The bottom of die 20 is above the table surface 50 of the sewing machine, as shown in Figs. 2 and 3 so that during this transfer movement the spangle has to be lowered a substantial distance. This is accomplished by making a portion of swinging arm 45 flexible and in order better to control receptacle 47 this flexible portion is formed as a lateral and preferably arcuate extension, as shown in Fig. 1, at the outer end of a

radial arm section. The inner end of this radial arm section of swinging arm 45 is secured to a vertical supporting post 51. The end of the flexible portion of the swinging arm 45 in which spangle receptacle 47 is located is preferably made of thin metal so that it may swing beneath the presser foot 3 and carry the spangle 48 to a position where the hole in the spangle is in alignment with needle 2. Spangle receptacle 47 has a substantially U shape in plan view, as shown in Fig. 1, the bottom of the U fitting the curvature of the spangle.

The bottom of the receptacle has a U-shaped slot to permit the passage of the needle 2 through the spangle while it is still held by receptacle 47. Guard member 46 is preferably an edgewise mounted arcuate strip so as to provide rigidity and enters between the toes of the presser foot 3 so as to terminate in close proximity to needle 2. It may be secured in position by means of screws 52 on the side of guide bar 18 of the punching mechanism.

It will be understood that swinging arm 45 carries spangle receptacle 47 to the sewing mechanism an instant previous to the entrance of the downwardly moving needle 2 through the aperture in the spangle 48, holds the spangle in position while the needle enters the spangle aperture and thereafter returns the spangle receptacle 47 to the punching mechanism, that is, to the dotted position shown in Figs. 1 and 2. The actuation of swinging arm 45 in this manner is accomplished by means of a spur gear sector 53 which is secured to vertical shaft 51 which supports arm 45. This shaft is mounted in suitable bearings in the frame 1 and sector 53 is engaged by gear teeth 54 on the face of the substantially vertical arm of feed actuating member 12, as shown particularly in Fig. 2. As this actuating member is keyed to shaft 10 and therefore rocks simultaneously with rock arm 8, and since needle 2 makes its downward stroke while the punching head 13 is making its upward stroke, or at the top thereof, spangle receptacle 47 is at its outer position beneath needle 2 at the time that actuating crank 6 is at the bottom of its stroke. Hence the "dwell" of this crank mechanism holds the spangle receptacle in stationary position, as described above, while needle 2 enters the opening of the spangle.

It will be understood that when it is desired to attach the spangles 48 in overlapping relation, as shown in Fig. 5, the gear train which interconnects the main shaft 4 of the sewing machine mechanism with operating shaft 5 will have a 1:1 ratio so that shaft 5 will make one revolution for each revolution of the sewing mechanism. This will cause the punching mechanism and transfer device to form and supply to the sewing mechanism one spangle for each operation of the sewing mechanism, that is, for each downward stroke of needle 2.

When it is desired to sew the spangles on in substantially tangential position, as indicated in Fig. 6, the gear ratio of the gear train above mentioned will be 2:1, so that the needle 2 will take two strokes for each operation of the spangle-forming and transfer mechanism. This will place one stitch, as indicated at 55, at the center of each spangle and a second stitch 56 between adjacent spangles. Further, should it be desired to increase the spacing of the spangles, as shown in Fig. 7, this can be done by increasing the gear ratio of the gear train by any desired amount. That is to say, the gear ratio can be such that 75

needle 2 of the sewing mechanism makes 3, 4 or any desired number of strokes to one revolution of shaft 5, or one operation of the spangle forming and transfer mechanism. In Fig. 7 the gear ratio is 1:3, that is, there are three revolutions of sewing machine shaft 4 to each single revolution of operating shaft 5, and accordingly two stitches 57 are placed between each of the spangles.

By means of the present invention a machine has been provided which is capable of forming and attaching spangles in substantially a single operation, that is to say, the spangles are punched from a strip of suitable material transferred from the punching mechanism to a sewing mechanism and sewed onto the fabric as they are individually punched and without releasing control of them. This greatly reduces both the cost of manufacture of the spangles, and the cost of sewing them on the fabric, or, in other words, it reduces the over-all cost of spangled dress fabric.

It will be understood that changes may be made in the construction of the machine illustrated and described above without departing from the spirit of the invention, the scope of which is set forth in the accompanying claims.

I claim:

1. In a machine for making and applying spangles to sheet material, mechanism for sewing spangles to said material, mechanism for forming complete individual spangles, a carrier for receiving an individual spangle from the forming mechanism and transferring it to the sewing mechanism, and means for actuating the forming mechanism and carrier in timed relation to the sewing mechanism to transfer complete individual spangles to the sewing mechanism as they are formed.

2. In a machine for making and applying spangles to sheet material, mechanism for attaching spangles to said material, mechanism for forming complete individual spangles from a blank strip, mechanism for feeding such strip to the forming mechanism, a carrier for receiving an individual spangle from the forming mechanism and transferring it to the attaching mechanism, and means for actuating said forming mechanism, said feeding mechanism and said carrier in timed relation to the attaching mechanism to transfer complete individual spangles to the attaching mechanism as they are formed.

3. In a machine for making and applying spangles to sheet material, mechanism for sewing spangles to said material, punching mechanism for forming complete individual spangles, mechanisms for feeding work to the punching mechanism, a device for receiving an individual spangle from the punching mechanism and transferring it to the sewing mechanism, and means for operating the punching mechanism, work feeding mechanism and the transferring device in timed relation to the sewing mechanism to transfer complete individual spangles to the sewing mechanism as they are punched from the work.

4. In a machine for making and applying spangles to sheet material, mechanism for sewing spangles to said material, mechanism for punching complete individual spangles from a blank strip, mechanism for feeding such strip to the punching mechanism, a device for receiving individual spangles from the punching mechanism and transferring them to the sewing mechanism, and means for operating the punching mechanism, strip-feeding mechanism and the

transferring device in timed relation to the sewing mechanism to transfer complete individual spangles to the sewing mechanism as they are punched from the strip.

5. In a machine for making and applying spangles to sheet material, mechanism for sewing individual spangles to said material, mechanism for forming individual spangles at a point remote from and out of the plane of the sewing mechanism, a yieldable carrier for transferring the individual spangles from the forming mechanism to the sewing mechanism, means for actuating the forming mechanism and the carrier in timed relation to the sewing mechanism to transfer the individual spangles to the sewing mechanism as they are formed, and means operable during said transfer for shifting the yieldable carrier from the plane of the forming mechanism to the plane of the sewing mechanism.

6. In a machine for making and applying spangles to sheet material, mechanism for attaching individual spangles to said material, mechanism for forming individual spangles, a carrier mechanism for transferring the individual spangles from the forming mechanism to the attaching mechanism including a receptacle for receiving an individual spangle from the forming mechanism and delivering the spangle to the attaching mechanism, means for actuating said mechanisms in timed relation to one another to transfer the individual spangles to the attaching mechanism as they are formed, and a stationary guard member cooperating with said spangle receptacle to hold the spangle within the receptacle as it is carried to the attaching mechanism.

7. In a machine for making and applying spangles to sheet material, mechanism for sewing individual spangles to said material, mechanism for forming individual spangles at a point remote from and out of the plane of the sewing mechanism, carrier mechanism for transferring the individual spangles from the forming mechanism to the sewing mechanism including an oscillating flexible arm, and means for actuating said arm in timed relation to the forming mechanism and sewing mechanism to transfer the individual spangles to the sewing mechanism as they are formed.

8. In a machine for making and applying spangles to sheet material, mechanism for attaching individual spangles to said material, mechanism for forming individual spangles at a point remote from and out of the plane of the attaching mechanism, a yieldable carrier mechanism for transferring the individual spangles from the forming mechanism to the attaching mechanism, means for actuating said mechanisms in timed relation to one another to transfer the individual spangles to the attaching mechanism as they are formed, said carrier having a receptacle for receiving a spangle from the forming mechanism and delivering it to the attaching mechanism, and a stationary guard member cooperating with said yieldable carrier to hold the spangle within said receptacle as it is carried to the attaching mechanism and serving as a cam to shift the yieldable carrier from the plane of the forming mechanism to that of the attaching mechanism.

9. In a machine for making and applying spangles to sheet material, mechanism for sewing individual spangles to said material, mechanism for forming individual spangles at a point remote from and out of the plane of the sewing

mechanism, carrier mechanism for transferring the individual spangles from the forming mechanism to the sewing mechanism including an oscillating resilient arm having at its outer end a receptacle for receiving a spangle from the forming mechanism and delivering it to the sewing mechanism, means for actuating said mechanisms in timed relation to one another to transfer the individual spangles to the sewing mechanism as they are formed, and a stationary guard member cooperating with said receptacle to hold the spangle therewithin as it is carried to the sewing mechanism and serving as a cam to bend said resilient arm and shift said receptacle from the plane of the forming mechanism to the plane of the sewing mechanism.

10. In a machine for making and applying spangles to sheet material, mechanism for sewing individual spangles to said material including a presser foot maintained in engagement with the surface thereof, mechanism for forming individual spangles at a point remote from said presser foot and out of the plane of the sheet material, carrier mechanism for transferring the individual spangles from the forming mechanism to the sewing mechanism including a flexible arm having at its end a receptacle for receiving a spangle from the forming mechanism and delivering it to the sewing mechanism, means for actuating said arm in timed relation to the forming mechanism and sewing mechanism to transfer the individual spangles as they are formed, the path of said receptacle terminating at a point beneath the presser foot, and a stationary guard member having a cam-like surface coating with the upper surface of said receptacle to guide the same from the plane of the forming mechanism to the plane of the material beneath the presser foot and to hold the spangle within said receptacle.

11. In a machine for making and applying spangles to sheet material, mechanism for forming individual spangles at a point remote from the point of attachment of the spangles to the sheet material, a carrier for transferring the spangles as they are formed to the point of attachment having a receptacle for receiving a spangle from the forming mechanism and delivering the spangle to the sheet material at said point of attachment, means for moving said carrier to transfer the spangles to said point of attachment, and a stationary guard member cooperating with said receptacle to hold the spangle within the same as it is carried to the point of attachment.

12. In a machine for making and applying spangles to sheet material, mechanism for forming individual spangles at a point remote from the point of attachment of the spangles to the sheet material, a carrier for transferring the spangles as they are formed to the point of attachment comprising a receptacle having an open side for receiving a spangle from the forming mechanism and an open end for delivering the spangle to the sheet material at said point of attachment, means for moving said carrier to transfer the spangles to the said point of attachment, and a stationary guard member cooperating with the open side of said receptacle to hold the spangle within the same as it is carried to the point of attachment.

13. In a machine for making and applying spangles to sheet material, mechanism for attaching individual spangles to said material, mechanism for forming individual spangles, said

75

mechanisms being in different planes, a carrier for transferring the individual spangles from the forming mechanism to the attaching mechanism including a receptacle for receiving an individual spangle from the forming mechanism and delivering the spangle to the attaching mechanism, means for actuating said mechanisms in timed relation to one another to transfer the individual spangles to the attaching mechanism as they are formed, and means operable during said transfer for shifting the carrier from the plane of the forming mechanism to the plane of the attaching mechanism.

14. In a machine for making and applying spangles to sheet material, mechanism for sewing individual spangles to said material including a presser foot mounted in engagement with the surface thereof, mechanism for forming individual spangles at a point remote from said presser foot, carrier mechanism for transferring the individual spangles from the forming mechanism to the sewing mechanism including an arm having at its end a receptacle for receiving a spangle from the forming mechanism and delivering it to the sewing mechanism, means for actuating said arm in timed relation to the forming mechanism and sewing mechanism to transfer the individual spangles as they are formed, the path of said receptacle terminating at a

point beneath the presser foot, and a stationary guard member coacting with the upper surface of said receptacle to hold the spangle within said receptacle during said transfer.

- 5 15. In a machine for making and applying spangles to sheet material, mechanism for attaching individual spangles to said material, mechanism for forming individual spangles at a point remote from and out of the plane of the attaching mechanism, a yieldable carrier for transferring the individual spangles from the forming mechanism to the attaching mechanism, means for actuating said mechanisms in timed relation to one another to transfer the individual spangles to the attaching mechanism as they are formed and to attach them to the sheet material, said carrier comprising a radial portion having at its outer end a laterally extending portion which terminates in a receptacle for receiving a spangle from the forming mechanism and delivering it to the attaching mechanism, and an arcuate stationary guard member coacting with the upper surface of said receptacle to hold the spangle within the same as it is carried 10 15 20 25 to the attaching mechanism and serving as a cam to lower the said receptacle from the plane of the forming mechanism to that of the attaching mechanism.

CESAR BUSTAMANTE.
